UNITED STATES PATENT OFFICE.

FRANK R. McBERTY, OF NEW ROCHELLE, NEW YORK, ASSIGNOR TO WESTERN ELECTRIC COMPANY, OF CHICAGO, ILLINOIS, A CORPORATION OF ILLINOIS.

SEMI-MECHANICAL TELEPHONE-EXCHANGE SYSTEM.

1,124,488.

Specification of Letters Patent.

Patented Jan. 12, 1915.

Application filed July 30, 1909. Serial No. 510,396.

To all whom it may concern:

Be it known that I, FRANK R. McBERTY, citizen of the United States, residing at New Rochelle in the county of Westchester and State of New York, have invented a certain new and useful Improvement in Semi-Mechanical Telephone-Exchange Systems, of which the following is a full, clear, concise, and exact description.

This invention relates to automatic switching systems for telephone exchanges, and has reference more particularly to improved sending apparatus by which the automatic action of selective line switching mechanism may be effected and controlled.

A semi-mechanical telephone exchange system to which the present invention is especially applicable involves apparatus whereby an operator at a central office may cause any calling line to be automatically switched into connection with any line wanted, by actuating a key or combination of keys designating such wanted line. The extension of the circuit to the line wanted is accomplished by mechanical switching appliances or automatic selectors which are governed by automatic sending or controlling apparatus, the action of which is brought about and determined by the actuated keys. A number of connecting circuits may be provided for each operator to use in answering calls, each connecting circuit having at one end means for uniting it with a calling line, and terminating at the other end in a mechanical selector switch. The sending apparatus may be brought into temporary association with any connecting circuit to control the selector switch or switches through which the circuit is successively extended in establishing the desired connection. When connection is completed to the line wanted, the sending apparatus is automatically disconnected and becomes immediately available for use with another connecting circuit.

Any suitable means may be provided in such a system for bringing a calling subscriber into telephonic communication with an operator at the central office and for uniting his line with the first of the series of automatic selector switches to be controlled by the operator in establishing the desired connection. For example, each line

may have an answering jack and line signal, as in the manual system, appearing before the operator who attends to the calls from such line, the operator's connecting circuit in such case terminating in an answering plug which will be inserted in the springjack of the calling line in the usual way. The operator after bringing her telephone (associated with the connecting circuit) into service and learning the number of the subscriber wanted, will register this number on a bank of keys similar to those of an adding machine, by depressing keys representing the digits of the number. The sending apparatus will thereby be brought into service and will operate in a distinctive manner according to the particular keys actuated, bringing about a succession of circuit-changing operations which will cause the selective line-switching mechanism to extend the circuit to the line so designated.

The sending apparatus includes as one of its principal elements a point-finder apparatus comprising a series of contact points or terminals adapted to be selected by corresponding keys, and a finder brush arranged to travel over these contacts in sequence and to coöperate with any selected point to cause the finder to be stopped at that point. Means are provided for setting the point-finder in operation by the depression of any key of a series, and the finder will then travel directly to the point selected by the particular key in question and stop there.

In accordance with the present invention, the finder after reaching the selected point is caused to travel to another stopping point, and the extent of travel required in this latter journey measures the extent of operation of a selecting mechanism and so determines a selection corresponding to the key. The first stage of operation of the point-finder apparatus, in reaching the point selected by the key, may be termed its "registering" action, and the second stage may be termed its "sending" action. The registering action will take place independent of the selector to be controlled, but in the sending operation the selector and the finder may be caused to operate in unison, as by pulsations of current corresponding to

the successive steps of each until the finder reaches the end of its "sending" journey, whereupon both finder and selector are stopped; the selection made being thus dependent upon the extent of the second journey of the finder.

According to the preferred arrangement, the keys are placed in reverse order to that of the register contacts. Assuming, for example, ten keys designated 0 to 9 and ten register contacts arranged in reverse order and designated 9 to 0. If the fourth key No. 3 is depressed, the register would be caused to advance seven steps so that on continuing the advance to control selection the register and selector would be moved four steps, bringing the register around to normal and stopping the selector at the desired point.

Where the sending apparatus is required to control a number of successive selective operations, as in operating one after another a train of selectors through which the circuit is successively extended, a number of point-finders may be arranged to register the different digits, respectively, of the number set up on the bank of keys, and the point-finders after the registration is completed may effect in sequence the different sending operations required. As each point-finder completes its sending operation, switching mechanism is automatically actuated to start the sending operation of the next finder. The switching means preferably provided for this purpose is a device which may be termed a mechanical relay, sequence switch, or controller, having motor mechanism operated or controlled by an electromagnet and provided with any required number of switch contacts arranged to be operated one after the other at different stages in its advance. This same device may control the seizure of the sender by a connecting circuit, the successive operations of the finders, the release of the keys, the restoration of the sending apparatus to normal, and in fact the whole series of actions concerned in the control of selections.

In the accompanying drawings I have illustrated a semi-mechanical telephone exchange system equipped in accordance with my invention, and I will now proceed to describe the same, reserving for the claims a statement of the parts, improvements or combinations intended to be covered herein.

Although for clearness specific terms are used in describing this system, it will be understood that such terms are not to be taken in all instances as defining the limits of the invention, for the novel features herein disclosed may be variously embodied in systems which may differ widely in details from the one shown in the drawings.

Figures 1, 2, 3, 4 and 5, when placed together in the order named (Figs. 1, 2 and 3

being one above the other and Figs. 3, 4 and 5 being joined side by side, with the lines which extend to the edge of each sheet connected to the continuations thereof on adjoining sheets) form a complete diagram of the elements of circuit and apparatus of a semi-mechanical telephone exchange system, so far as involved in uniting two subscribers' lines for conversation. Fig. 1 represents a bank of keys arranged in three sets representing "hundreds," "tens" and "units" digits, respectively. Fig. 2 represents the "registers" corresponding to the three sets of keys. Fig. 3 represents the sequence switch apparatus which controls the successive operations of the sending apparatus. Fig. 4 represents the calling subscriber's line and the operator's connecting circuit, together with the first selector, which in the small exchange illustrated is a "hundreds" selector. Fig. 5 represents the final selector to which the circuit may be extended by the first selector, and also represents the called line to which the final selector may make direct connection. Fig. 6 is a front view of one of the point-finders or registers, such as are diagrammatically indicated in Fig. 2. Fig. 7 is a side view thereof. Fig. 8 is a sectional plan view on line 8-8 of Fig. 7. Fig. 9 is a plan view. Fig. 10 is a detail plan view of the arm carrying the traveling contact brush. Fig. 11 is a detail sectional view of the upper portion of the mechanism, taken on line 11-11 of Fig. 7. Figs. 12, 13 and 14 are detail views of the three cams which operate switch springs. The same letters of reference indicate corresponding parts throughout the several figures.

Mechanism of selectors.—The mechanism of the selectors shown diagrammatically in Figs. 4 and 5 may be, for example, substantially as shown and described in my previous application, Serial No. 418,126 filed February 27, 1908; but an understanding of their general features of construction and mode of operation may be had by reference to the diagrams herein. Each selector has a rotary shaft 50, carrying a frame 60 at the outer end of which a number of contact brushes 51, 52, 53, are pivoted in position to travel over contact terminals 61, 62, 63, mounted in rows concentric with the shaft. Spring tongues 54, 55, 56, extending from insulated metal plates 41, 42, 43, respectively, press against projecting arms of the brushes, and besides making electrical connection therewith, tend to rock the brushes on their pivots in a direction to throw their forward or contact ends outwardly. The brushes are electrically connected in sets of three, and each set is normally latched against the thrust of the spring tongues 54, 55, 56, by a catch 57 which is normally held in the path of movement of the rear ends of said brushes. As shown, the catches 57 are insu-

lating bars mounted on spring latch-arms 58, which are the free ends or tongues of a spring metal plate 59 fixed to the rotary frame 60.

8 In order to bring any set of brushes into position to engage the contacts over which they travel, they must be released by tripping the corresponding catch 57 to allow the brushes to be rocked upon their pivots by 10 their springs 54, 55, 56. This tripping of the brushes is accomplished by a trip-bar 64 which is pivotally mounted on an axis 65 and has at its edge a series of projecting lugs 66 in position to be moved into the paths of 15 the respective latch-arms 58 when the trip-bar is rocked on its axis. It is intended that only one of the several sets of brushes shall be selected and tripped in a given operation, and the trip-bar is therefor inclined at an 20 angle so that the tripping lugs 66 will face positions successively reached in the rotation of the brush-carrier frame. The trip-bar will be actuated to thrust forward its tripping lugs only for a moment when the end 25 of the latch-arm controlling the desired set of brushes reaches an angular position just in advance of that occupied by the particular lug which is at the proper height to engage that arm. The movement of the trip- 30 bar may be accomplished by a tripping-magnet 67 the movable armature 68 whereof is mechanically connected to said bar.

A segmental metallic plate 70 is mounted in position to be engaged by the contact ends 35 of the brushes as they are tripped, this plate extending to the end of the "trip range"—that is, through the arc traversed by the brushes as one set after another throughout the series is brought into position to be 40 tripped. At the end of the trip range the bank of line terminals 61, 62, 63, begins. These terminals are arranged in sets of three, corresponding in relative positions to the 45 relative positions of the brushes by which they are to be traversed, and the different sets are arranged in an arc in position to be successively reached in a point-to-point rotary advance of the brushes.

To restore the brushes to their latched 50 position when the selector returns to normal, an insulating bar 95 is arranged to be passed over by the brushes in their return journey, the brushes in passing over this bar being raised thereby against the tension of their 55 springs, until their beveled rear ends slip over the catches 57.

The motor mechanism for rotating the brush carrier frame may be as follows: An iron plate 73 is mounted to rotate with the 60 shaft 50, but in such a manner that it may be given a flat-wise or tilting movement into engagement with one or the other of two iron driving rollers 74, 75, which are located on either side of its axis and are constantly 65 driven by shaft 76. An electromagnet 77,

which I term the power-magnet, is arranged to magnetize the driving rollers 74 and 75 to cause them to attract the iron plate 73. Said plate is provided with cam surfaces, so that in the normal position of the apparatus the 70 surface on one side of the axis 50 will be closer to the driving wheel 75 than the surface on the other side of said axis is to the driving wheel 74. Normally, therefore, when the power-magnet is excited the plate 75 75 80 85 90 95 100 105 110 115 120 125 130 135 140 145 150 155 160 165 170 175 180 185 190 195 200 205 210 215 220 225 230 235 240 By the operation of the selector, the conductors connected to the plates 41, 42 and 43 may be connected respectively to any set of three stationary line terminals in any horizontal level, by first tripping the multiple 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 7

set of brushes which travels over the required level, and then causing the brush carrier to rotate until the selected brushes reach the desired set of terminals in that level.

5 In the particular system shown in the drawing, each selector is intended thus to select any one of a hundred sets of terminals, there being three terminals in each set, for the two line conductors and the test conductor, respectively, of a telephone circuit. Each selector will therefore be considered to have thirty brushes, ten sets of three each, and three hundred stationary terminals arranged in ten levels corresponding to the 10 ten sets of brushes, with ten vertical rows of three terminals each in each level, or ten vertical rows of thirty terminals each in all. For simplicity in the diagram, there are shown only two sets of brushes and a few 15 of the contact terminals in the two corresponding levels.

Sending apparatus.—The sending apparatus for controlling the selective operations includes a bank of keys adapted to be actuated by the operator, said keys being arranged in separate sets corresponding to the different digits of line-numbers of the system. The simple exchange chosen for illustration is designed for 1000 lines, and the 20 bank of keys shown therefore comprises a set of "hundreds" keys, a set of "tens" keys and a set of "units" keys, each set consisting of ten keys numbered from 0 to 9 inclusive. Each key in a set or row, as shown diagrammatically in Fig. 1, is arranged when depressed to close a contact controlling a circuit individual to the keys, and also to close another contact controlling a circuit common to all the keys of the row. Means are 25 provided for registering or "storing up" the number indicated by any combination of keys actuated, and for using this number as a basis for governing a series of selecting operations. Each key is adapted to be held 30 in its depressed position until the registers shown diagrammatically in Fig. 2 and in detail in Figs. 8 to 14 "take up" the number indicated, by moving their respective point-finders 201 to the points selected by the 35 corresponding keys. When the number indicated is so registered the keys may be automatically released. As shown, each key has a plunger 101 for actuating a set of contacts; and the means shown for locking the plungers in their depressed positions is a magnet 40 having long pole-pieces extending along under all the keys of a set and adapted to engage armatures 103, which are carried on the plungers of individual keys and are arranged to be moved into contact with said pole-pieces when the keys are depressed. The magnet when energized is not strong enough to draw down a key from its normal 45 position, but is strong enough to hold fast the armature of any depressed key, and so to

lock such key in its depressed position. The keys may be provided with the usual springs (not shown) for restoring them to normal position when the retaining magnet is de-energized.

70 The number indicated by the depressed keys and "stored up" on the registers by the distinctive positions to which their respective point-finders are advanced, will be made the basis of controlling successive selecting 75 operations; and in the present case the registers are intended to act also as controlling steppers to operate in unison with the distant selectors and thereby determine the selections according to the numbers which they 80 have previously registered. The sending apparatus also includes sequence switch mechanism by which different devices or circuits are brought into service one after another as the operation progresses.

85 *Mechanism of registers, controlling steppers and sequence switches.*—The device shown in detail in Figs. 8 to 14 combines the functions of a register, to take up the number indicated by one of the keys of a set, and 90 of a controlling stepper to operate at a subsequent stage in unison with a selector to control the selecting operation according to the number registered. It also embodies the same mechanical principle as the sequence 95 switch, in that a single electromagnetic motor mechanism operates a number of switches in any desired sequence, the different switching operations being successively performed as the rotary element successively reaches 100 different positions in its advance.

The rotary element 200 of the mechanism shown is a vertical shaft carrying at its upper end a finder-brush or wiper 201 adapted as the shaft rotates to travel over and 105 make contact successively with stationary terminals 202. In the form shown the brush is adapted to break contact with each terminal before making contact with the next. Connection may be made to the moving 110 brush 201 by means of a stationary brush 207 bearing on a slip-ring 208 carried by the rotary element, said slip-ring being electrically connected with the metallic mounting of said brush 201. Eleven stationary 115 terminals are shown, arranged at equi-distant points around a circle; and the mechanism is adapted to allow the brush to stop either upon any of said terminals, or upon intermediate points between said terminals. There are thus twenty-two "positions" or 120 half-steps for the rotary element, as indicated in the diagram Fig. 2, of which position No. 22 will be considered as normal. A movement of the finder from one position to the next, as from a terminal to the following insulating segment, will be considered as a half-step, a full step being a movement from terminal to terminal.

125 Preferably a constantly-driven power- 130

shaft is arranged to be mechanically coupled to drive the rotary element of the register, through the agency of magnetically-controlled clutch mechanism. Thus, as shown, the rotary element carries an iron disk 203 which serves as a rotary pole-piece, so to speak, for a clutch-magnet or motor-magnet 206; and an iron friction-driving disk 204 carried by a constantly-rotating shaft 205 is adapted to be drawn into engagement with the disk 203 when and while the motor magnet 206 is excited. The rotary element carries a series of cams 209, 210, 211, for actuating switches 213, 214, 215, respectively, as shown most clearly in the diagram Fig. 2. The cam 209 is adapted to hold the spring 213 away from the contact anvil 216 except in the normal position (22) when said contact is allowed to close. Cam 210 holds spring 214 away from both its alternate contacts 217 and 218 in the normal position, which in this case is No. 22, and also in position 1, but is adapted to cause the spring to engage contact 218 in the "even" numbered positions 2, 4, 6, etc., up to and including 20, and to engage contact 217 in the intermediate or "odd" numbered positions 3, 5, 7, etc., up to and including 21. In the positions having even numbers the traveling brush 201 rests on terminals, and in the intermediate or odd-numbered positions the brush 201 rests on insulation between terminals. The cam 211 operating the switch 215 is for the purpose of closing a local circuit for the power-magnet 206 while the rotary element is in transit from one position to the next, to insure that said element may come to rest accurately at any position. Said cam 211 is adapted therefore to cause the switch lever 215 to engage contact 220 between each position and the next, and to break such contact as each position is reached. The pivoted switch lever 215 carries a roller 219 which rides over the teeth of the cam 211, and a spring 221 acting upon the lever 215 causes the roller in descending the slope of each tooth to push the cam slightly, so that after the power is cut off the roller continues to push in until it reaches the bottom of the notch between two teeth, thus insuring the accurate positioning of the rotary element. It will be understood that this arrangement of cams and contacts applies only to the particular form of mechanism intended for operation with the particular circuit arrangement shown in Fig. 2.

The sequence switches which are indicated diagrammatically in Figs. 4 and 5 are precisely similar in mechanical construction to the combined register, stepper and switch shown in Figs. 8-11, except that they will not be provided with the finder-brush 201, and the stationary contacts 202, but will have instead a large number of cams and

switches, arranged to perform the more numerous successive switching operations hereafter to be described.

For clearness in the diagrams, the switch springs of the sequence-switches of Figs. 3, 4 and 5 are not shown in actual relations, but are so located as to give the clearest arrangement of circuits, and the operating cams are also omitted, the positions of the rotary element in which contacts are closed being indicated by the numbers placed adjacent to such contacts. For example, contact 409 (Fig. 4) is closed in the first, second and thirteenth positions, and this is indicated by the numbers 1, 2, 13, adjacent thereto. Each sequence switch, however, has a switch-lever corresponding in function to the switch-lever 215 of the mechanism before described—that is, for the purpose of closing a local circuit for its motor magnet between the regular positions, and in the diagram those switches are distinguished by being shown as somewhat heavier than the ordinary switch-springs, and as having a cam roller. The numbers appearing adjacent to each such switch-lever upon the opposite side from its contact, indicate that the switch is open in the positions so numbered and closed in all other positions. That is to say, in Fig. 4, for example, the numbers 1, 3, 4, 5, 6, 7, 8, 9, 13, 14, 15, indicate that the local switch is open in the first position, closed between the first and third, open in the third, closed between the third and fourth, and so on. Where the numbers applied to the local switch are not consecutive, as, 1, 3, 4, etc., for example, it is thus indicated that while the local switch is open in the positions named, it is closed continuously between such positions. Thus when the device leaves the first position it will be carried through to the third without a stop, due to such continuous closure of the local circuit for its motor magnet.

Operation of system.—A further detailed description of the apparatus used in the system, and a statement of the electrical connections of each part will be unnecessary, as devices of known types are indicated by the usual conventional symbols, and the electrical connections are clearly shown in the diagram. Certain of the usual appliances require in an actual telephone system, such, for example, as the operator's telephone set, have not been shown because their connections and manner of use will be well understood by those skilled in the art, and to show them in detail would too greatly complicate the diagram. Several batteries are shown, and for convenience in tracing circuits are designated by different reference characters, but it will be understood that in practice a single central battery would be employed, connected as indicated. The organization and mode of operation of the system can

best be understood by tracing the successive operations or steps involved in automatically extending connection from a calling line to a line called for, transmitting the necessary signals, making the requisite tests, establishing a talking circuit, and finally disconnecting the lines and restoring the apparatus to normal condition. These operations, however, can be more readily followed if a rough outline is first given.

The function of the sequence-switches may be readily understood from the following: Each stage in the operation of a selector, for example, requires the establishment of a given set of circuits, and the sequence-switch is the means for accomplishing the successive shifts required. Each selector has associated with it a sequence-switch which is normally in a position to establish circuits by which it may be initially taken for use. As each stage of its operation is completed, a circuit is closed for the motor magnet of its sequence switch, which will advance to another position to bring about the next operation, and in so doing will prepare a new circuit for its own motor magnet to be closed when such next operation in turn is completed.

The selective operations in the particular system shown are controlled by the sending apparatus in the following manner: A stepping circuit is established over the line through a line relay at the selector and through a stepping magnet at the sender. The line relay while excited closes a circuit for the power magnet of the selector to cause the selector to advance its brushes, and in such advance the interrupter of the selector makes and breaks a short-circuit of the line, so causing current to be applied in intermittent impulses to the stepping magnet at the sender, causing the armature of said magnet to vibrate. This armature in its vibration opens and closes a circuit to the motor magnet of a point-finder device, so that the point-finder device is thereby caused to advance in unison with the pulsations of current received over the line from the selector. The operation of the interrupter at the selector does not, however, deprive the line relay of current, and the selector thus continues to advance its brushes. When the point-finder at the sender reaches a predetermined point selected by a corresponding key, a circuit is closed for the stop relay which opens the line circuit and so releases the line relay at the selector. The first time this occurs the line relay in recovering breaks a short-circuit about the trip magnet of the selector, allowing said trip magnet to trip a set of brushes, the particular set which is tripped being dependent upon the number of steps which the rotary element of the selector has advanced. The third or test brush of the set which was

tripped, in striking the ground plate 70 of the selector closes a circuit for the line relay, which is again excited, and thus immediately again short-circuits the trip magnet, the excitation of the power magnet having been undisturbed. When all the brushes have passed the trip range the sequence switch is advanced to a position in which the branch from the power magnet circuit containing the trip magnet is permanently opened, so that the subsequent release of the line relay at the end of another sending operation (or at the end of a testing operation in the case of hunting for an idle trunk) may deprive the power magnet of current and bring the brushes to rest upon the set of terminals which have thus been selected. As each point-finding operation is completed by the sending apparatus, the line or stepping circuit is opened, as before described, but the circuit is closed again when the next sending or selector-controlling operation is to occur, to permit the stepping magnet to be operated as before, and the various selections thus proceed under control of the sending apparatus until the desired line is reached, whereupon the sending apparatus is disconnected from the circuit. The operations of testing and signaling the called line and the sending of a busy signal in case the line selected is busy, may be controlled by successive operations of the sequence-switch at the final selector.

The successive steps involved in extending connection from a calling line to a line wanted may now be traced. It will be assumed that the subscriber at station No. 491, Fig. 4, has signalled the central office in the usual way by removing his receiver from its hook, thus closing the line circuit and causing the line relay to close a local circuit for the line signal lamp 492. The operator will answer the call in the usual way by inserting her answering plug 493 in the spring-pick of the calling line and depressing her listening key to bring her telephone set (not shown) into circuit so that she may hear the number of the subscriber wanted. The insertion of the answering plug completes a circuit for the cord relay 495, and the subsequent operation of the listening key closes a special contact 494 thereof which completes a circuit for the motor magnet 497 of the sequence-switch associated with the first selector. This circuit may be traced from battery 498 through the motor magnet 497, normally closed contact 499 of the sequence-switch, contact 494 of the listening key, front contact of the cord relay 495 to earth. The sequence-switch therefore begins to advance, and by reference to the numerals near the local switch lever 410, it will be seen that the local circuit for the motor magnet remains closed from the first position to the third, so

that the sequence-switch advances to its third position without stopping. At the second position a contact 411 is closed, controlling a common branch from the supervisory signal lamps 412 and 413 which are thus brought into service, under the control of the usual supervisory relays 414 and 415 respectively. As the sequence-switch of the first selector reaches the third position it 5 closes a contact 416 which completes a circuit for a relay 300 (Fig. 3) which governs the seizure of the sending apparatus by the connecting circuit which has been put into use. This circuit is traced from battery 301 through the sender-seizing relay 300 to conductor 418 which is multiplied to the contacts 416 of the sequence-switches of all the connecting circuits of an operator's position, the circuit being completed through the contact 416 of the one which has been taken 10 for use, to earth. At the same time a contact 417 is closed which extends a circuit 419 for the sequence-switch motor magnet 407 to the sending apparatus, to be completed at contact 303 of the sequence switch associated with said sending apparatus when said last-mentioned sequence-switch reaches its third position. This will be 15 when all the registers have taken their positions in response to the depression of the keys.

The circuit 418 controlled at contact 416 furnishes a means by which the sequence-switch of the sending apparatus can be controlled by any connecting circuit; and the circuit 419 controlled at contact 303 of the sequence-switch associated with the sending apparatus furnishes a means whereby the sending apparatus may exercise a reciprocal control over the sequence switch of the first selector. When the relay 300 is excited, a circuit is closed for the motor magnet 317 of the sender sequence-switch, which thereupon moves to its second position. The operator having now communicated with the calling subscriber and learned the number of the line wanted, depresses keys (Fig. 1) representing the digits of such number. For example, if line 950 were called, the operator would depress the hundreds key 20 No. 9, the tens key No. 5, and the units key No. 0. As shown in Fig. 2, there is a register for each set of keys, that is, a hundreds register, a tens register and a units register, 25 the construction of which has heretofore been described. The keys in each set are adapted to select points in reverse order upon the register corresponding to such set. In the case assumed the hundreds key No. 9 will ground the terminal at position No. 2 of the hundreds register, so that the point-finder of said register, after reaching the terminal so selected by the hundreds key No. 9 will take ten full steps from terminal to 30 terminal in continuing its journey around to

the starting point or normal position No. 22. The tens key No. 5 will ground the terminal at position No. 10 of the tens register, so that the point-finder of said register, after reaching the terminal so grounded, 35 will have to take six full steps to reach normal. The units key No. 0 will ground the terminal at position No. 20 of the units register, so that the point-finder of said units register upon arriving at said position No. 20 will have to take one full step farther to reach normal. In other words, each key will select a point distant from the final stopping point a number of full steps corresponding to the numeral of the key, plus 40 one.

When a hundreds key (for example, key No. 9) is depressed, a circuit may be traced from the battery 205 (Fig. 2) through the motor magnet 206 of the hundreds register, 45 back contact of the finder relay 226 thereof, conductor 227, through contact 304 of the sender sequence-switch to conductor 104, and thence to ground at the closed contact 106 of the depressed hundreds key. The 50 motor magnet 206 of the hundreds register being thus excited moves the point-finder of said register until the brush 201 reaches the point grounded by the depressed hundreds key, in this case the terminal at position No. 2, whereupon a circuit is completed from battery 228, through relay 226 of the hundreds register, to the finder brush 201 and the terminal on which said brush rests, and so to ground at the depressed 55 hundreds key. Similarly, any tens key when depressed closes a circuit which may be readily traced for the motor magnet of the tens register, which circuit is opened by the finder relay of said register when the point selected by such key is reached by the tens finder brush. Likewise, any units key when depressed closes a circuit for the motor magnet of the units register, which circuit is opened by the finder relay thereof when the point selected by such key is 60 reached by the units finder brush.

The relay 226 in attracting its armature breaks the circuit previously traced for the motor magnet 206 and connects the 65 grounded wire 227 to a wire 229 leading through a contact 305 of the sender sequence-switch to the motor magnet 317 of the latter, whereby said sequence-switch is advanced to the third position. In this position contacts 306 and 307 are closed from the front and back contacts respectively of the stepping relay 308 to the alternate contacts of the "escapement" switch spring 214 of the hundreds register, so that the step relay 308 may now control the "sending action" of the register to advance its brush 201 from the point selected by the key around to the normal position No. 22. The 70 intermittent action of the stepping relay 120 75 80 85 90 95 100 105 110 115 120 125 130

to accomplish this result will be brought about by the action of the interrupter of the first selector, as will presently be described.

- As soon as the sender sequence-switch 5 moved to its third position at the time the hundreds register found the point selected by the depressed hundreds key the contact 303 was closed, completing the circuit for the motor magnet 407 of the first selector sequence-switch, moving said switch to its fourth position. In this position a circuit is closed by which the test relay 420 of the first selector is connected in series with the stepping relay 308 of the sender, the test relay closing a circuit for the power-magnet of the selector, and the interrupter of the selector being brought into service to intermittently short-circuit the line leading back to the stepping relay.
- 20 The circuit for the test relay may be traced from the battery 421 through said test relay 420, contacts 422 and 423 of the sequence-switch, to conductor 424, through the stepping relay 308 of the sender (Fig. 3) through the back contact of the stop relay 309, through contact 310 of the sender sequence-switch to earth.

The test relay 420 in closing its front contact completes a circuit from battery 425 through the power magnet 77 of the first selector, contact 426 of the sequence-switch, front contact of test relay 420 to earth. The power-magnet attracts the tilting disk 73 into engagement with the driving wheel 75, and the brush carrying frame of the selector is started to rotate, this rotation being continued as long as the test relay 420 remains excited. As the frame begins to rotate the interrupter arm 84 is vibrated as the roller 85 is carried over the toothed segment 88. As the roller rides up on each tooth the contact 86, 87, is closed, completing a circuit which may be traced from battery 421 through test relay 420, contact 422, wire 427, back contact 426 of trip magnet 67, contact 86, 87, to earth at 429, thus short-circuiting the stepping relay of the sender.

The stepping relay 308 at the sender is 50 excited by current in the circuit previously traced, as soon as the first selector sequence-switch closes contacts 422 and 423. Said stepping relay in closing its front contact completes a circuit for the motor magnet of the hundreds register, which may be traced from battery 205 through said motor magnet 206, contact 218 of the "escapement" switch spring thereof, wire 232, contact 306 of the sender sequence-switch, through the 55 front contact of the stepping relay to earth, causing the hundreds register to be moved from the position in which the finder-brush came to rest upon the selected terminal to the next or intermediate position, in which 60 said brush rests upon an insulating seg-

ment between terminals. In the case assumed, in which the register had previously come to rest upon the selected terminal at position No. 2, it will, when the stepping relay 308 is first excited, move to the next position No. 3. In this position the escapement spring 214 engages its alternate contact 217 which is connected by wire 234, through contact 307 of the sender sequence switch, to the back contact of the stepping relay.

As the interrupter roller 85 of the first selector rides up to the first notch and closes the short circuit 427 previously traced, the stepping relay at the sender will be released and will allow its armature to fall back and complete the circuit for the motor magnet 206 of the hundreds register, whereby said register is moved to the next position, in which the "escapement" contact 218 is again closed, bringing the motor magnet under control of the front contact of the stepping relay.

As the selector finishes a complete step and the interrupter roller 85 reaches the bottom of the next notch, the contact 86, 87, is opened, breaking the short circuit 427 and permitting the flow of current again to the stepping relay, which in closing its front contact again advances the hundreds register. As successive impulses are delivered to the stepping relay 308, the selector and the hundreds register are thus advanced in unison from step to step until the register has reached a final stopping point, namely, position No. 22, the number of steps required having been determined by the position in which the finder brush 201 came to rest in its previous registering action under control of the depressed hundreds key.

As the register in its step-by-step escapement movement reaches the final stopping position No. 22, it closes a contact 216, the result of which we shall presently see will be to cause a set of brushes to be tripped at the selector, the particular set tripped being dependent upon the number of steps which the selector has taken in unison with the hundreds register before said register reached the stopping point.

The closing of contact 216 completes a circuit which may be traced from battery 311 (Fig. 3) through the stop relay 309 (controlling the continuity of the stepping circuit) to conductor 312, through contact 123 of the sender sequence-switch, to wire 314, through contact 216 at the hundreds register to earth. The closing of contact 216 at the hundreds register also closes a contact through the motor magnet 315 of 325 a timing controller or auxiliary sequence-switch, the function whereof will hereafter appear.

When the stop relay 309 is excited, and breaks the stepping circuit 424, the test re-

- lay 420 at the first selector is released and opens its front contact, thus breaking the short circuit of the trip magnet 67 of said first selector. The power magnet 77 is not released, however, as it is held up by current from battery 425 flowing through said power magnet 77 and trip magnet 67 in series, and through contact 430 of the selector sequence-switch to earth.
- 10 While the brush carrying frame of the selector continues to rotate, therefore, the trip magnet 67 is excited and rocks the trip bar 64 to thrust the projecting lugs 66 into the paths of the latch arms 58. As the 15 brush carrier frame continues its travel the first latch arm to reach one of the tripping lugs 66 will be engaged thereby and detained sufficiently to release the three brushes normally held by said latch arm, 20 allowing these brushes to be rocked upon their pivots by their springs 54, 55, 56, and so thrust into contact with the grounded metal plate 70. The particular set of brushes which is thus brought into service 25 will depend upon the number of steps through which the selector had advanced before the trip magnet was excited. In the case assumed, where the hundreds key No. 9 was depressed, the register and selector 30 had taken ten full steps in unison before the arrival of the hundreds register at its final stopping point resulted in the opening of the stepping circuit and the energization of the trip magnet at the selector. In these 35 ten steps the latch arms of the first nine sets of brushes (counting from the bottom up) had successively passed the points at which they might have been tripped, leaving the latch arm of the tenth set of brushes in position to be engaged by the projecting lug of the trip bar as the selector continues to advance. In other words, the set of 40 brushes which has been tripped and brought into service corresponds to the hundreds key which was depressed. In the present 45 case the hundreds key No. 9—that is to say the 10th hundreds key—caused the 10th set of brushes to be tripped and brought into service.
- 50 As soon as the brushes make contact with the grounded metallic segment 70 the test relay 420 is immediately excited again by current flowing from battery 421 through said test relay, contacts 422 and 423, to brushes 51 and 53 in multiple, to the plate 70 and ground. The test relay in drawing up its armature again closes the short circuit of the trip magnet, said trip magnet being excited only long enough to trip a set 55 of brushes.
- 60 As soon as the brush carrier shaft of the selector first began to rotate, the cam 80 forced the spring 81 against contact anvil 82, completing a circuit from battery 408 through motor magnet 407 of the sequence-
- switch, contact 432, contact 82, spring 81, to earth. The sequence-switch is thus advanced to the 5th position in which its motor magnet is connected through a contact 433 to the alternate contact anvil 83 of the cam-⁷⁰ actuated spring 81. The cam 80 is shaped so that when the rotary element of the selector has advanced all the brushes beyond the trip range the spring 81 will be allowed to engage contact anvil 83, thus completing⁷⁵ a circuit for the motor magnet of the sequence-switch, and causing said switch to be advanced to the 6th position.
- 70 In leaving the 5th position the contact 423 is broken, but contact 422 remains closed⁸⁰ in the 6th position, leaving the test relay connected in a circuit to the third or test brushes 53 of the ten sets in multiple. As only one set of brushes has been brought into an operative position, however, only⁸⁵ the test brush of this particular set may be considered.
- 75 The sequence-switch in leaving the 5th position opened the contact 430 controlling the circuit for the trip magnet, thus opening⁹⁰ the branch by which the power magnet was previously held up in series with the trip magnet, leaving said power magnet dependent for its excitation upon current derived from the front contact of the test relay,⁹⁵ which will now govern the further advance of the selector brushes in "hunting" an idle trunk. The sequence-switch in reaching the 6th position also closes a contact 484 by which its motor magnet 407 is connected¹⁰⁰ to the back contact of the test relay, so that when the test relay is deenergized, as it will be when an idle trunk is found, the sequence-switch will be moved from the 6th position to the 7th, in which the test relay will be¹⁰⁵ cut off and the sender leads 424 and 434 simply connected to the selector brushes.
- 80 The segment 88 of the selector is provided with a long tooth 89 to be engaged by the cam roller of its interrupter while the¹¹⁰ brushes are passing between the end of the trip range and the beginning of the range containing the line terminals. As the brushes pass off the end of the grounded metal segment 70 the interrupter roller is¹¹⁵ passing over the long tooth 89, so that the short circuit 427 is closed and the test relay maintained excited. As the brushes reach the first set of terminals, however, the roller 85 of the interrupter enters the first notch¹²⁰ (in the particular machine under consideration) and the interrupter contact 86, 87, is opened, breaking the short circuit 427 and leaving the test relay 420 dependent for its excitation upon a circuit which may be completed through the third test brush 53 of the set which has been tripped to a test terminal 63 which will be connected to earth if the line tested is busy. All the sets of line terminals reached in the travel of a given set of¹²⁵ 86

brushes are the terminals of trunk lines leading to final selectors, any of which will have access to the same group of lines. The trunk lines will be multiplied to all the first 5 selectors; and any particular first selector in endeavoring to make connection with a trunk line leading to a final selector of the group desired will be required to hunt over the terminals of trunk lines representing 10 final selectors of the desired group, until an idle trunk is found. The advance of a given set of brushes of the first selector over the line terminals in the corresponding level will therefore be a hunting operation. The 15 brushes will stop upon any set of terminals only if a certain electrical condition exists at the test terminal of the set, such condition in the present case being the absence of a ground connection. As will hereafter be 20 shown, the test terminals of all trunk lines which are busy will be connected to earth, and circuit will therefore be maintained for the test relay of the hunting selector through the test brush 53 to earth as long 25 as the test brush is passing over the terminals of busy lines. As the test brush reaches each terminal the circuit for the test relay 420 through the interrupter contact 86, 87, is broken; and as soon as the test terminal 30 of an idle line is reached, there being no ground connection upon such test terminal, no circuit will exist for the test relay 420, and said relay will be released, breaking the circuit of the power magnet 77 and 35 causing the selector brushes to come to rest upon the terminals of the line so tested and found idle. The test relay 420 in recovering also closes a circuit which may be traced from the battery 408, through the motor 407 of the sequence-switch, contact 484, and through the back contact of the test relay to earth. The sequence-switch is thus moved from the 6th to the 7th position, in which the circuits for the test relay and 40 power magnet of the selector are open, and the sender leads 424 and 434 connected through contacts 436 and 437 to the line brushes 51 and 52, respectively; and so to the conductors 501 and 502 of the trunk line 45 leading to the final selector. Contacts 463 and 464 are also closed, connecting the test brush 53 to earth, and so establishing the grounded or "busy" condition for all the multiple terminals of the trunk line selected.

Returning now to a consideration of the sending apparatus, it will be remembered that when the register, acting as a "stepper" or "sender" reached its final stopping position No. 22, it closed a contact 216, completing a circuit for the stop relay 309 which opened the stepping circuit and so caused the test relay at the first selector to be released and the trip magnet to be excited. 55 The stepping circuit should be held open

long enough for the selector to travel through a distance sufficient to permit the tripping of a set of brushes, after which the stepping circuit should be closed at the sending end when the next selecting operation is to be performed.

For the purpose of holding the stepping circuit open during the time necessary to trip a set of brushes, the timing controller or auxiliary sequence-switch 320 is provided, 75 as shown in Fig. 3. The motor magnet 315 of this timing controller is connected through the contact 313 of the main sender sequence-switch to the conductor 314 which is grounded at contact 216 when the hundreds register reaches its final stopping point, so that said motor magnet 315 is excited in multiple with the stop relay 309. The timing controller after leaving its first or normal position runs through to the 7th 80 position without a stop, and during the time required for this travel the sequence-switch controlling the sender is maintained in the 4th position in which contact 319 controlling the stepping circuit is opened. The stepping circuit is also held open at the back contact of relay 309, which is maintained excited by a circuit closed at contact 336 of the timing controller while the latter is running from its 1st to its 7th position. As 85 soon as the timing controller reached the second position the sender sequence-switch was moved from the 3rd to the 4th position, the circuit for this operation being traced from the battery 316, through the 90 motor magnet 317 of said sequence-switch, contact 318 thereof, contact 319 of the timing controller, to earth. The sender sequence-switch is thus moved from the 3rd to the 4th position, closing contact 321, from 95 which when the timing controller reaches its 7th position a circuit will be completed through contact 322 of said timing controller to earth, whereby the motor magnet 317 will be again excited and the sender sequence-switch moved to the 5th position. In 100 this position the contact 323 is closed, whereby a circuit will be completed for the motor magnet 317 provided the tens and units registers have both performed their registering 105 actions and taken up the positions selected by the depressed tens and units keys. This circuit may be traced from the battery 316, through motor magnet 317, contact 323, wire 324, through the front contacts of the finder 110 relays of the tens and units registers in series, to conductor 236, thence through a contact 325 of the sender sequence-switch, to a wire 337, through the contact 107 of the depressed units key, and contact 110 of the depressed tens key to earth. The sender sequence-switch is thus moved from the 5th to the 6th position, in which the stepping circuit is closed at the sender end at contact 327. In the 6th position the contacts 328 115

and 329 are also closed, connecting the front and back contacts respectively of the stepping relay to the escapement contacts of the tens register.

- 5 The stepping circuit having been held open for a period of time measured by the passage of the timing controller from the 1st to the 7th position to allow time for the tripping of the set of brushes at the selector. 70
- 10 is now closed at contact 327 to await the next set of stepping impulses which will now be transmitted from the final selector, Fig. 5. As soon as the brushes of the first selector come to rest upon the terminals of 75
- 15 a trunk line leading to an idle final selector, the stepping circuit is established as follows: from battery 504 at the final selector, through the line relay 520 thereof, to trunk line conductor 501 leading to the terminal 80 51 of said trunk line at the first selector, to the brush 51 of said selector, contact 436, sender lead 424, stepping relay 308, back contact of stop relay 309, contact 327, sender lead 434, contact 437, brush 52 of the first selector, trunk line terminal 62, trunk conductor 502, through normally closed contact 505 of the sequence-switch associated with the final selector, to earth. The line relay 520 of the final selector corresponds in function to the test relay 420 of the first selector. When excited by current in the circuit just 85
- 16 opened, it closes at its front contact a circuit from battery 506, through the motor magnet 507, normally closed contact 528 of the sequence-switch and front contact of the line relay 520 to earth. The sequence-switch associated with the final selector is thus moved to its second position, in which a circuit is closed from battery 525, through power magnet 77 of the final selector, contact 526 90
- 17 of the sequence-switch, through the front contact of the line relay 520 to earth. The power magnet being thus excited, the brush carrier is started in rotation, and as the interrupter roller 85 passes over its toothed 95
- 18 segment it makes and breaks the contact 86, 87 of said final selector, establishing at each closure of said contact a circuit from battery 504, through line relay 520, conductor 527, contact 522 of the sequence-switch, back contact 528 of the trip magnet of the final selector, through the interrupter contact 86, 87, to earth, thus short-circuiting the line and causing the stepping relay 308 at the 100
- 19 sender to be deenergized each time said short circuit at the final selector is closed. 105
- When the stepping circuit is first established, connecting the line relay of the final selector and the stepping relay 308 of the 110
- 20 sender in series, said stepping relay 308 in closing its front contact completes a circuit through sequence-switch contact 328 for the motor magnet 206 of the tens register by way of the escapement contact 218 of said tens register; and when the stepping relay 115
- 21 is deenergized it completes at its back contact a circuit for said motor magnet of the tens register, through the sequence-switch 329 and escapement contact 217 of the tens register. As the armature of the stepping 120
- 22 relay is vibrated the tens register is thus stepped around to its final stopping position No. 22, as already described with reference to the hundreds register, the number of steps being dependent upon the particular 125
- 23 tens key which was depressed. When the tens register reaches its final stopping position it closes its contact 216, completing a circuit through sequence-switch contact 335 for the stop relay 309 of the sender, as before described in the operation of the hundreds register. The stop relay 309 opens the stepping circuit, as before described, and causes a set of brushes to be tripped at the final selector. The set of brushes tripped 130
- 24 corresponds to the tens key which has been depressed. 135
- As the brush carrier of the final selector begins to rotate, the cam 80 of said final selector causes the contact 82 to be closed, completing a circuit for the motor magnet 507 of the final selector sequence-switch, moving said switch to the third position. This is the position in which a set of brushes 140
- 25 may be tripped: and as the line relay 520 is released when the tens register completes its operation and causes the stepping circuit to be opened by relay 309, said line relay 520 in opening its front contact breaks the short circuit of the trip magnet, leaving the power magnet and trip magnet connected in series in a circuit which may be traced from battery 525 through the power magnet 77 and trip magnet 67 of the final selector, to contact 539 of the sequence-switch, and through the back contact 551 of a polarized 145
- 26 busy test relay 550 to earth. The operation of tripping the brushes is the same as previously described with reference to the first selector, and when the test brush of the set 150
- 27 which is tripped makes contact with the grounded metallic segment 70 of the selector a circuit is completed for the line relay 520 through contact 538 of the sequence-switch, to the test brush 53, segment 70, and earth. This short-circuits the portion of the line leading back to the sender, and the line relay being again energized, short-circuits the trip magnet 67 of the selector. 155
- As the brushes leave the segment 70 at the 160
- 28 end of the trip range, and enter upon the range of line terminals, the interrupter in passing over the long tooth 89 of the segment 88 maintains a short circuit of the line, through the interrupter contact 86, 87. 165
- 29 When all the brushes of the final selector have passed the trip range, the cam 80 allows the contact 83 to be closed, completing a circuit for the motor magnet 507 of the sequence-switch associated with the final se- 170
- 30

- lector, whereby said switch is moved from the 3rd to the 4th position. In this position the trip magnet is permanently cut out of circuit by the opening of contact 530.
- 5 In the final selector, the segment 88 is provided with an extra notch in advance of the notches corresponding to the positions in which the brushes rest upon the line terminals. As the interrupter roller 85 of the 10 final selector passes down from the long tooth into this first notch in the "line terminal range" in advance of the notches representing line-connecting positions, the short circuit controlled by interrupter contact 86 is broken, and the first of the new series of selecting impulses is applied to the stepping relay 308 at the sender. The stepping circuit which was opened at the sender when the tens register completed its operation is closed again before the first of the units selecting impulses is applied at the final selector at the time the interrupter roller 85 enters the first or preliminary notch in the line range. The stepping circuit was held open at the sender during the operation of the timing controller, while the brushes at the selector were being tripped. When the tens register completed its operation it caused the stop relay 309 to be excited in multiple with the timing controller 315 which advanced from its 7th to its 13th position, holding the stop relay 309 excited by a circuit from battery 311, through said stop relay 309 to conductor 312, and through contact 336 of the timing controller to earth. The timing controller in reaching its 8th position closes a circuit for the motor magnet 317 of the sender sequence-switch, whereby the latter is advanced from its 6th to its 7th position, breaking the circuits between the contacts of the stepping relay and the register apparatus. When the timing controller reaches its 13th position the circuit is again completed for the motor magnet of the sender sequence-switch, through contacts 321 and 322, advancing the sequence-switch to its 8th position, in which the front and back contacts of the stepping relay are connected through contacts 338 and 339 respectively, of the sender sequence-switch to the escapement contacts 218 and 217, respectively, of the units register. The stop relay 309 is deenergized when the timing controller reaches its 13th position. In which contact 336 is opened. The sending apparatus is now ready to receive the second or units set of selecting impulses from the final selector. The first or preliminary impulse which is applied to the stepping relay 40 at the time the interrupter roller enters the first notch preliminary to the line range causes the stepping relay to complete at its front contact a circuit from ground, through contact 338 of the sender sequence-switch, escapement contact 218 of the units register, through the power magnet of said register to the free pole of battery 250.
- In the case assumed, where units key No. 0 was depressed, the finder brush of the units register came to rest in position No. 20, so that said units register will now be moved, as the stepping relay receives its preliminary impulse, to position No. 21. Now as the interrupter roller 85 at the final selector leaves the "preliminary" notch and 75 rides up on the next tooth, closing contact 86, 87, and short circuiting the line, the stepping relay 308 being deenergized, closes at its back contact a circuit for the motor magnet 206 of the units register, through escapement contact 217 and sequence-switch contact 339, whereby the units register is moved to its final stopping position No. 22, again closing a circuit for the stop relay 309 (this time through sequence-switch contact 85 340) to cause said stop relay 309 to open the stepping circuit. Now as the interrupter roller 85 at the final selector enters the following notch, corresponding to a position of the selector brushes upon the first vertical row of line terminals, the short circuit 527 controlled at the interrupter contact 86, 87, is broken; and as the line or stepping circuit is now broken at the sender, the line relay will be deenergized, and in recovering will 95 open the circuit of the power magnet controlled at the front contact of said relay, whereby the tripped set of selector brushes will be brought to rest upon the first set of line terminals in the previously chosen tens 100 level. The first set of line terminals thus chosen corresponds to the first units key No. 0 which was depressed.
- At the end of the last sending operation, under control of the units register, the stop relay 309 and the motor magnet 315 of the timing controller were excited, as previously described, the timing controller running from the 13th to the first position by reason of the closure of the local switch contact 336 between the 12th and the 1st positions. When the timing controller reaches the 14th position, the circuit is completed from battery 316, through the motor magnet 317 of the sender sequence-switch, contact 318 thereof, contact 319 of the timing controller, to earth. The sequence-switch is thus moved to the 9th position. When the timing controller reaches its first position the motor magnet of the sender sequence-switch is again excited in a circuit through contact 321 of said switch and contact 322 of the timing controller to earth. The sender sequence-switch has twelve positions, but the local switch contact 345 is closed between the 9th and the 1st positions, so that upon leaving the 9th position the sequence-switch runs through to the 1st or normal position without stopping in the 10th, 11th or 12th positions. When the sender sequence-switch leaves 115
- 60 120
- 65 125

the 9th position the contact 346 is opened, breaking the circuit for the locking magnets 102 of the keys (Fig. 1) whereby said keys are released and allowed to return to their 5 normal positions. As the sequence switch reaches its 9th position it closes contact 303 and completes a circuit which may be traced from battery 408 (Fig. 4) through motor magnet 407 of the sequence-switch associated with the first selector, contact 417 thereof, wire 419, contact 303, to earth. The sequence-switch of the first selector is therefore moved from its 7th to its 8th position, in which contacts 436 and 437 are open, 10 disconnecting the sender leads 424 and 434 from the first selector. Contacts 461 and 462 are closed in the 8th position of the first selector sequence-switch, connecting the link conductors of the cord circuit through to the 15 brushes 51 and 53 of the first selector, and so through the trunk line conductors 501 and 502 to the final selector.

As the sequence-switch of the first selector leaves its 7th position the contact 416 is 20 opened, breaking the circuit for the sender-controlling relay 300 (Fig. 3) which is released. The sending apparatus is now completely restored to normal condition, all circuits being open between the registers and 25 the sender sequence-switch, and contacts 327 and 310 controlling the stepping circuit being also open.

When the line relay 520 of the final selector is released at the end of the final sending operation, a circuit is closed from battery 506, through the motor magnet 507 of the final selector sequence-switch, contact 584 of said sequence-switch, back contact of the line relay, to earth; whereby the sequence-switch is moved to the 5th position. 30 In this position the busy test of the called line is made. When the test brush 53 of the final selector comes to rest upon the terminal of the called line, a test circuit is completed 35 from the test terminal of said line to the test brush of the selector, and through contact 552 of the sequence-switch, windings 553 and 554 of the polarized test relay 550 and contact 555 of the sequence-switch, to 40 earth. The test relay 550 is marginal in its operation. It is adjusted to attract its armature upon current received from the test terminal of a line that is free, but will not respond to current received from the test terminal of a line that is busy, the test relay in 45 the latter case being shunted by a path from the test terminal of a busy line to earth at the already-existing connection.

As the final selector sequence-switch 50 reaches the 5th position, a circuit will be completed for its motor magnet, whereby 55 said sequence-switch will be advanced to the 9th or busy-back position, at which it will stop, if the line tested is busy, but if the line 60 tested is free a circuit will be maintained for

the motor magnet of the sequence-switch until the 9th or busy-back position has been passed. If the line tested is busy the circuit for the motor magnet will be from battery 506, through said motor magnet 507, contact 70 541 of the sequence-switch, and back contact 551 of the test relay to earth. The contact 541 is maintained from the 5th to the 8th position, and the local contact 510 is also closed between the 5th and 9th positions, so 75 that the sequence-switch will in any event reach the 9th position. In this position the free pole of the busy tone interrupter 560 is connected through contact 542 of the sequence-switch to the trunk conductor 502. 80 The circuit is thus intermittently completed from the battery, 450 bridged between the windings of the repeating coil in the cord circuit (Fig. 4) through supervisory relay 415, out over the conductor 502 of the trunk line, to the final selector, through contact 542 of the sequence-switch thereof, and interrupter 560, to earth. The supervisory lamp 413 before the operator will thus be caused to flash, indicating to her that the line for 90 which connection has been asked is busy.

If the line tested is free, the test relay will complete a circuit from battery 506, through motor magnet 507 of the final selector sequence-switch, to a contact 540 thereof, and 95 front contact of the test relay 550, to earth. This circuit is maintained until after the sequence-switch leaves the 9th position, and the local switch contact 510 is closed between the 9th and 11th positions, so that the sequence-switch instead of stopping at the 9th or busy-back position, will run through to the 11th position.

As soon as the sending operation was completed, and the contact 461 closed at the sequence-switch of the first selector, the line relay 520 at the final selector was excited by current from battery 504 flowing through said line relay to trunk conductor 501, back through the first selector and contact 461 of 105 its sequence-switch, to the ground connection 452 of the repeating coil in the cord circuit. The line relay at the final selector being thus excited at the time its sequence-switch reaches the 11th position, a circuit will be 110 completed from battery 506, through the motor magnet 507 of the sequence switch, contact 508 thereof, front contact of the line relay 520, to earth; whereby the sequence-switch will be moved to the 13th position, 115 contact 510 being closed between the 11th and 13th positions.

In the 13th position the contacts 536 and 537 are closed, connecting the poles of the ringing generator 556 to the line brushes 51 and 52 of the selector, thus applying ringing current to the called line. When the subscriber answers the call by removing his telephone from its hook, the increased current flowing through the supervisory relay 120 125 130

557 associated with the final selector causes said relay to close a circuit from battery 506, through motor magnet 507 of the sequence-switch, contact 543 thereof, front contact of 5 the supervisory relay 557, to earth; whereby the sequence-switch is moved to the 14th or talking position. In this position the contacts 561 and 562 are closed, completing the talking circuit for the trunk line, through 10 the repeating coil 570.

In the 14th or talking position of the final selector sequence-switch, the supervisory relay 557 will receive current from the battery 571 bridged between two of the windings of 15 the repeating coil, and will control at its front contact a path to ground from the trunk line conductor 502, thereby controlling the supervisory relay 415 in the cord circuit, which in turn controls the supervisory signal 20 lamp 413 in the usual manner.

Disconnection.—When the operator receives the disconnect signal, indicated in the usual way by the lighting of the supervisory lamps 412 and 413, she takes down 25 the connection by removing the answering plug 403 from the spring jack of the calling line. The cord relay 405 is thus released and closes a circuit from battery 408, through the motor magnet 407 of the sequence-switch 30 associated with the first selector, contact 472 thereof, and back contact of cord relay to earth. The local contact 410 of the sequence-switch being closed between the 8th and 13th positions thereof, said sequence-switch 35 will be carried through to the 13th position, whereupon a circuit will be completed from battery 408, through motor magnet 407, contact 473, back contact of supervisory relay 415, wire 474, contact 475 of the sequence-switch, to earth. The sequence-switch will 40 thus be carried to the 14th or "return" position in which a circuit will be completed from battery 425, through power magnet 77 of the selector, contact 476, back contact of 45 the test relay, to earth. The power disk 73, being off-normal, its surface is nearer to the return driving roller 74 than to roller 75, so that said disk will be attracted into engagement with the roller 74, and the brush-carrying frame of the selector will be 50 rotated back to normal position. As the cam 80 in the return movement closes the contact 82, a circuit is completed from battery 408, through motor magnet 407 of the sequence-switch, contact 482, contact 82, spring 81, to earth, whereby the sequence-switch is moved to its 15th position. When 55 the rotary brush carrier of the selector reaches its normal position the cam 80 opens contact 82 and closes contact 83, completing a circuit from battery 408, through motor magnet 407, contact 483 of the sequence-switch, contact 83 closed by the cam, to earth. The sequence-switch of the first selector has sixteen positions, but the local 60

contact 410 is closed between the 15th position and the 1st or normal position, so that the sequence-switch is carried through to its normal position. Upon leaving the 15th position the contact 476 is opened, breaking 70 the circuit for the power magnet, and stopping the rotation of the brush carrier frame. Both the first selector, and its sequence-switch are now in normal position.

When the operator removed the plug from 75 the springjack, and the sequence-switch of the first selector left its 8th or talking position, contact 461 was opened, thereby breaking the circuit of the line relay 520 at the final selector, which was excited during 80 the connection. The line relay 520 in recovering establishes a circuit from battery 506, through motor magnet 507 of the sequence-switch associated with the final selector, through contact 584 thereof, and back 85 contact of line relay 520, to earth. The sequence-switch is therefore moved to the 15th position, in which contacts 561 and 562 are open, and contact 576 closed, the latter completing a circuit from battery 525, through 90 the power magnet 77 of the final selector, contact 576 and back contact of the line relay 520, to earth. The brush carrier of the selector is now rotated back to normal position, as previously described with reference 95 to the first selector. When the cam 80 of the final selector in returning closes the contact 82, a circuit is completed from the battery 506, through the motor magnet 507, contact 532 of the sequence-switch, contact 100 82 and spring 81, to earth. The sequence-switch is thus moved to the 16th position, and as the rotary element of the selector reaches its normal position cam 80 closes contact 83 of the final selector, and a circuit 105 is completed from battery 506, through motor magnet 507, contact 533 of the sequence-switch, contact 83 and spring 81, to earth. The sequence-switch of the final selector has seventeen positions, but as the local contact 110 510 is closed between the 16th and the 1st positions, the sequence-switch upon leaving the 16th position, runs through to the 1st or normal position. All the apparatus of 115 the system is now in the normal condition. 116

I claim:

1. The combination with a point-finder having a series of contact points and a finder brush arranged to traverse said points in sequence, of a series of keys adapted to 120 select corresponding points in said series, said keys being arranged in reverse order from the arrangement of the corresponding contact points in the series, selector mechanism, and means for operating said selector mechanism in conformity with the advance of the finder brush beyond a selected point.

2. The combination with a series of contact-points, of a finder adapted to traverse 125 said points in sequence, a series of keys

- adapted to select corresponding points in reverse order, means brought into action by any key for advancing the finder over the series of points, step-by-step mechanism, means for bringing the same into action as the finder reaches the selected point, and means for operating said step-by-step mechanism in unison with the advance of the finder from point to point over the remainder of the series. 3. The combination with a point-finder, of a series of keys, means controlled by any key for displacing the point-finder to a definite extent determined by the particular key, automatic step-by-step mechanism for returning the point-finder to its normal position, selector mechanism, and means controlled by said step-by-step mechanism in returning said point-finder for operating said selector mechanism. 4. The combination with a point-finder, of a series of keys, means controlled by any key for displacing the point-finder to a definite extent determined by the particular key, automatic step-by-step mechanism adapted to further advance said point-finder to a final stopping point, a selector, means for operating said selector in unison with said step-by-step mechanism in such further advance of the point-finder, and means operated as the point-finder reaches its final stopping point, for arresting both the selector and the step-by-step mechanism. 5. The combination with a point-finder, of a series of keys, means controlled by any key for rotating said point-finder to a point predetermined by the key, means for continuing the travel of said point-finder to a final stopping point, a selector having a movable switch-member, and means for advancing said switch-member to an extent measured by the travel of the point-finder from said selected point to said final stopping point. 6. The combination with a point-finder having a motor magnet and means for exciting the same to advance said point-finder, of a finder relay, a circuit therefor adapted to be completed by said finder in reaching a predetermined point, a stepping relay, and means operated by said finder relay for establishing a circuit for said motor magnet under control of said stepping relay. 7. The combination with a point-finder, of continuously-acting motor mechanism adapted to advance said point-finder to a selected point, mechanism adapted to cause said point-finder to advance step-by-step to a final stopping point, a selector and means for operating the same under control of said point-finder in its step-by-step movement. 8. The combination with a point-finder, of continuously-acting motor mechanism, an electromagnetic clutch controlling the application of said motor mechanism to drive said point-finder, means for exciting said clutch to carry said point-finder to a selected point, a step magnet, a distant selector, a stepping circuit uniting said selector and step magnet, means for applying intermittent current impulses in said stepping circuit and for operating the selector in unison therewith, alternate circuits for said electromagnetic clutch closed through the agency of said step magnet when excited and released, respectively, and a switch, operated as the point-finder reaches a final stopping point, adapted to open said stepping circuit. 9. In a sending apparatus, the combination with a series of keys, of a rotary point-finder, means brought into action by any key for advancing said point-finder in a continuous movement, means controlled by the point-finder in arriving at a point selected by the actuated key for stopping such advance of the point-finder, and mechanism brought into service by the point-finder in arriving at such selected point adapted to cause said point-finder to rotate step-by-step in the same direction around to the original starting point. 10. In a sending apparatus, the combination with a series of keys, of a rotary point-finder, continuously-acting motor mechanism, a clutch magnet, a relay, a circuit therefor adapted to be completed by the point-finder in reaching a point selected by the particular key actuated, said relay being adapted to open the circuit of said clutch magnet, and step - by - step mechanism brought into service by said relay in its response, adapted to cause said finder to continue its rotary movement step by step to the original starting point. 11. The combination with a point-finder apparatus, having a motor magnet and means operated thereby for advancing the finder, of a finder-relay, a circuit therefor adapted to be completed by the finder in reaching a selected point, a stepping relay, means controlled by the response of said finder relay for establishing a circuit for said motor magnet under control of said stepping relay, a stepping circuit whereby said stepping relay may be intermittently excited, a stop relay adapted to open said stepping circuit, and a circuit for said stop relay adapted to be completed by said finder upon a predetermined advance beyond the first-mentioned selected point. 12. The combination with a movable switch element adapted to travel through successive positions, of a motor magnet and mechanism operated thereby for moving said switch element from one position to another, a finder relay, a circuit therefor adapted to be completed by the switch element in reaching a selected position, a stepping relay, and means controlled by the response of said finder relay for establishing

- a circuit for said motor magnet under control of said stepping relay. 65
13. The combination with a movable switch element adapted to travel through successive positions, of a motor magnet and mechanism controlled thereby for moving said switch element from one position to another, a stepping relay, contacts closed by the movable switch element in alternate positions adapted to bring said motor magnet under control of back and front contacts, respectively, of said stepping relay. 70
14. The combination with a sender circuit including a stepping relay, of a series of sender mechanisms, each having an operating electromagnet, a sequence-switch adapted to bring the magnets of said sender mechanisms one after another under control of said stepping relay, and means for advancing said sequence-switch as each sender mechanism completes its operation. 75
15. The combination with a point-finder and a series of contact points adapted to be traversed thereby, of a series of keys adapted to select corresponding points, means controlled by any key for advancing the finder to the corresponding selected point, a step - by - step mechanism, and means brought into action by the finder in reaching the selected point, for advancing said finder and said step-by-step mechanism in unison until said finder reaches a predetermined point beyond the first mentioned selected point. 80
16. In an automatic switching system, the combination with a sender circuit, of a series of sender mechanisms, a sequence-switch adapted to bring said sender mechanisms successively into operative relation to said sender circuit, and means actuated by each sender mechanism in completing its operation, for advancing said sequence-switch. 85
17. The combination with a selector having a controlling magnet 420, of a sender apparatus having a magnet 308 and step-by-step mechanism operated thereby, a selecting circuit including said magnets 420 and 308, a timing controller adapted when set in operation, to effect a change in the electrical condition of said selecting circuit to which said controlling magnet 420 is responsive, for a predetermined period, whereby an operation of the mechanism of the selector is produced, and means controlled by said step-by-step mechanism at a predetermined stage of its movement for setting said timing controller in operation. 90
18. The combination with a selector having a controlling magnet 420 and a motor mechanism brought into action through the agency of said magnet when deenergized, of a sender apparatus having a stepping magnet 308, a stepping circuit extending between the selector and sender, and including said magnets 420 and 308, means operated by the selector for intermittently short-circuiting the stepping magnet 308, step-by-step mechanism operated by the intermittent excitation of said stepping magnet, an automatic timing device set in operation through the agency of said step-by-step mechanism at a predetermined stage of its movement, and switching means for maintaining the stepping circuit open during the operation of said timing device. 95
19. In combination, a controlling apparatus comprising a plurality of contact points, a movable contact member movable over said points in two stages in a predetermined order, a series of contact devices corresponding to the contact points but connected thereto in an order reverse from that in which the points are engaged by said movable contact member and mechanism having a movable part governed by the extent of movement of said contact member in the second stage. 100
20. The combination with a selecting apparatus, of a controlling apparatus therefor, comprising a movable contact member, a plurality of contact points with which the movable member co-operates, a set of contact devices, means for imparting a preliminary movement to the contact member into co-operation with a point determined by a contact device, and means for causing the further movement of the contact member in control of the selecting apparatus and independently of the contact device. 105
21. The combination in a controlling apparatus, of a movable contact member, motor means for advancing said member, means for selecting a predetermined point in the path of travel of said contact member, means for stopping the advance of said member at said predetermined point, a stepping relay and means for causing the further advance of said contact member under the control of said stepping relay. 110
22. The combination in a controlling apparatus, of a movable contact member, motor means for advancing said member, means for selecting a predetermined point in the path of travel of said contact member, means for stopping the advance of said member at said predetermined point, a stepping relay, and means under the control of said stepping relay operating to return said contact member to its normal position. 115
23. The combination in a controlling apparatus, of a movable contact member capable of movement in two complementary stages, electromagnetic controlling mechanism for determining the movement of said member in the first stage, means for causing the further movement of said contact member in the second stage, and mechanism hav- 120
- 125

ing a movable part governed in its movement by the extent of the movement of said member in the second stage.

24. The combination in a controlling apparatus, of a movable contact member capable of movement in two complementary stages in the same direction, controlling mechanism for determining the movement of said member in the first stage, means for causing the further movement of said contact member in the second stage, and automatic switching mechanism governed in the extent of its movement by the extent of the movement of said member in the second stage.

25. The combination in a controlling apparatus, of a movable contact member capable of rotary movement in two complementary stages, electromagnetic controlling mechanism for determining the movement of said member in the first stage, means for causing the further movement of said contact member in the second stage, and switching mechanism having a movable member the degree of movement of which is controlled by the extent of the movement of said member in the second stage.

26. The combination in a controlling apparatus, of a movable contact member capable of rotary movement in two complementary stages in the same direction, controlling mechanism for determining the movement of said member in the first stage, means for causing the further movement of said contact member in the second stage, and mechanism having a movable part governed in its movement by the extent of the movement of said member in the second stage.

27. The combination in a controlling apparatus, of a movable contact member capable of rotary movement in two stages, the second of such stages in all cases accomplishing the return of said member to normal, electromagnetic controlling mechanism for determining the movement of said member in the first stage, means for causing the further movement of said contact member in the second stage, and apparatus having a movable part governed in its movement by the extent of the movement of said member in the second stage.

28. The combination in a controlling apparatus, of a movable contact member capable of rotary movement in two stages in the same direction, the second of such stages in all cases accomplishing the return of said member to normal, controlling mechanism for determining the movement of said member in the first stage, means for causing the further movement of said contact member in the second stage, and apparatus having a movable part governed in its movement

by the extent of the movement of the said member in the second stage.

29. The combination in a controlling apparatus, of a movable contact member, motor means for moving said member in two complementary stages, electromagnetic controlling mechanism governing said motor means for determining the movement of said member in its first stage, and an automatic switch having a movable contact governed in the extent of its movement by the extent of movement of said member in its second stage.

30. The combination in a controlling apparatus, of a movable contact member capable of movement in two stages, motor means for driving said member, a constantly operating source of power, controlling mechanism adapted to bring said source of power into co-operative relation with said motor means to move said member in its first stage, and controlled apparatus governed in its movement by the extent of movement of said member in its second stage and controlling the co-operative relation of said source of power and motor means to move said member in such second stage.

31. The combination in a controlling apparatus, of a movable contact member capable of movement in two complementary stages, a series of contact devices for determining the extent of movement of said member in its first stage, motor means for driving said member, and apparatus having a movable part governed in its movement by the extent of movement of said member in its second stage.

32. The combination in a controlling apparatus, of a movable contact member capable of movement in two complementary stages, electromagnetic controlling means for determining the movement of said member in its first stage, means for causing the further movement of said contact member in the second stage, and selector apparatus governed in its selection by the extent of movement of said member in the second stage.

33. In combination in a controlling apparatus, of a movable contact member capable of movement in two complementary stages, motor means for driving said member, contact devices for determining the movement of said member in its movement in the first stage and selector apparatus governed in its selection by the extent of movement of said member in the second stage.

34. The combination in a controlling apparatus, of a movable contact member, means for moving said member in two complementary stages in the same direction, controlling mechanism for determining the

movement of said movable member in the first stage, and controlled apparatus governed in its movement by the extent of movement of said member in the second stage, and means operated by said controlled apparatus to drive said member during its movement in such second stage.

35. The combination in a controlling apparatus, of a point finder capable of movement in two complementary stages, electromagnetic controlling mechanism for determining the movement of said point finder in the first stage, means for causing the further movement of said contact member in the second stage, and apparatus having a movable part governed in its movement by the extent of the movement of said point finder in the second stage.

36. The combination in a controlling apparatus, of a point finder capable of movement in two complementary stages, keys for determining the movement of said point finder in the first stage, motor means for driving said point finder, and a selector governed in its movement by the extent of movement of said point finder in the second stage.

37. The combination in a controlling apparatus, of keys, mechanism adapted in one movement to register the indication of any key when depressed, and a selector operating under the control of said mechanism during a subsequent movement thereof.

38. In a controlling apparatus, the combination with keys and a selector, of mechanism adapted to register the indication of

any key when depressed and thereafter upon its restoration to normal to govern the operation of said selector.

39. In a controlling apparatus, the combination with keys and a selector, of mechanism adapted to register the indication of any key when depressed, and thereafter upon its restoration to normal and independent of the depressed key to govern the operation of said selector.

40. The combination in a controlling apparatus of a controlling device and a controlled device, means for moving said controlling device in two complementary stages in the same direction, the movement in the last stage governing the movement of the controlled device, and electromagnetic means governed by the movement of the controlled device for moving the controlling device in the second stage of its movement.

41. The combination in a controlling apparatus of a controlling and a controlled device, automatic means for moving the controlling device in two complementary stages, manually operable keys, said automatic means being governed in the first stage of the movement of the controlling device by said keys, and in the second stage by the movement of the controlled device.

In witness whereof, I hereunto subscribe my name this 28th day of July A. D., 1909.

FRANK R. McBERTY.
